Primary Examiner — Michael C Stout(74) *Attorney, Agent, or Firm* — Snell & Wilmer LLP(57) **CLAIM**

The ornamental design for a bottle as shown and described.

DESCRIPTION

FIG. 1 is a front perspective view of a bottle showing my new design;

FIG. 2 is a front view of FIG. 1;

FIG. 3 is a rear view of FIG. 1;

FIG. 4 is a right side view of FIG. 1;

FIG. 5 is a left side view of FIG. 1;

FIG. 6 is a top view of FIG. 1; and,

FIG. 7 is a bottom view of FIG. 1.

The broken lines in the figures depict portions of the top cap that form no part of the claimed design.

1 Claim, 5 Drawing Sheets(56)
